DESIGN FOR A GRANULAR MATERIAL
CONTAINER

Daryll D. Eklund, Council Bluffs, Iowa

Application May 2, 1947, Serial No. 138,748

Term of patent 3½ years

(Cl. D44—22)

To all whom it may concern:

Be it known that I, Daryll D. Eklund, a citizen of the United States, residing at Council Bluffs, in the county of Pottawattamie and State of Iowa, have invented a new, original, and ornamental Design for a Granular Material Container, of which the following is a specification, reference being had to the accompanying drawing, forming part thereof.

Fig. 1 is a perspective view, and Fig. 2 is a top plan view of a granular material container, showing my new design.

I claim:

The ornamental design for a granular material container, substantially as shown.

DARYLL D. EKLUND.
